KNITTING MACHINE

Volkhart Walter Mehnert, Siegmar-Schonau, Germany, assignor to Elite-Diamantwerke Aktiengesellschaft, Siegmar-Schonau, Germany, a company of Germany

Application April 29, 1937, Serial No. 139,664
In Germany May 2, 1936

10 Claims. (Cl. 66—64)

The invention relates to knitting machines and more particularly to those of flat type.

One object of the invention is to provide a new guiding and controlling mechanism for the carriage and a driving device having obliquely positioned friction rollers which are pressed against a rotating shaft to control the direction of motion and the speed of the carriage according to the angle of their position. In these driving devices the shaft and consequently also the friction wheels with their control mechanism are situated laterally of the carriage guides and, when they are mounted on the carriage itself, they load the latter in one-sided manner, so that jamming may result. In order to prevent this, according to the present invention, the casing or housing carrying the friction rollers is mounted in special guide tracks and coupled with the carriage in such a way that only the axial forces for the carriage movement are transmitted, but no loading moments.

Another object of the invention is to suspend the sliding carriage on rails situated above and distant from the needle bed to prevent jamming and to guide the sliding carriage more accurately all over the needle bed.

The control mechanism, according to the invention, which brings about the change-over of the friction rollers from the oblique position for one direction of movement into the oblique position for the opposite direction, is so arranged that, upon the change of direction, a uniform retardation and re-acceleration of the highest possible amount is produced, eliminating the danger of the given speed being altered unintentionally and the danger of the rollers remaining in the middle position, where they are without effect upon the axial carriage movement and avoiding furthermore, the slipping of the friction rollers on the rotating shaft.

The invention is illustrated by the accompanying drawings, which show a schematic representation of the arrangement according to the invention.

Fig. 1 being a side elevation of an embodiment of the machine, showing the friction roller casting in partial section and the gear which controls the reversing and speed of the carriage,

Fig. 2 a rear view of the machine along the line II—II of Fig. 1,

Figs. 3 and 4 a section through the control lever along the line III—IV of Fig. 1; Fig. 3 illustrating the middle position and Fig. 4 the striking position at one side,

Fig. 5 is a view of the driving levers,

Fig. 6 a plan on the casing carrying the friction rollers.

In the drawings the carriage 1 bearing the knitting cams 2 is placed on the needle bed 3 by being suspended through U-shaped bridges 4 the upper parts of which form horizontal cross rods 5. The U-shaped bridges 4 bear the roller pairs 6 and 7.

The carriage is supported by the rollers 6 on the rails 8 and is guided in lateral direction by 10 the rollers 7. The rails 8 for their part are secured on both front ends 9 of the needle bed 3 by supports 10, one of which only is shown in Fig. 2 on the left side.

The upper part of the carriage 1 is provided 15 with a projection 11 connected to a projecting part of a driving gear casing 13 through a coupling member 12. The casing 13, carrying the friction rollers 14, is movably arranged on guiding rods 16 attached to the frame of the knitting machine behind the needle bed 3 and serves 20 to move the carriage 1 along the needle bed. The friction rollers 14 are held by supports connected to spindles 18 journaled in the casing 13 and are pressed against the driving shaft 15 by means 25 of springs. The driving shaft may be driven by a motor (not shown) with a constant number of rotations. The axis of the friction rollers 14 may be adjusted in a parallel or inclined direction relative to the axis of the driving shaft 15 by means 30 of an adjusting device connected to the above mentioned spindles 18 and to be described later on. If the friction rollers 14 are in neutral position, i. e., if the axes of the friction rollers 14 are in parallel relationship with respect to the 35 axis of the driving shaft 15, the driving shaft will rotate the friction rollers 14 but will not cause a movement of the casing 13 and the carriage 1 connected therewith along their guiding means 16 and 8 respectively, as the friction rollers roll 40 upon the shaft 15 along a circle. If, however, the friction rollers 14 are in active position, i. e., if the axes of the friction rollers 14 are inclined to the axis of the driving shaft 15, the driving shaft will rotate the friction rollers and cause a 45 movement of the casing 13 and the carriage 1 connected therewith along their guiding means 16 and 8 respectively, as the friction rollers roll upon the shaft 15 along a helical line and their supports are in a fixed position with respect to 50 the casing 13. The speed of the carriage 1 depends on the adjusted pitch of the helical line or angle between the axes of the friction rollers 14 and driving shaft 15. Thus, the operation of the driving mechanism is similar to the cooperation 55

between a threaded spindle and a nut with the exception that the pitch may be changed by adjusting the relationship between the rollers 14 and the shaft, while the pitch of a threaded spindle cannot be changed. Depending on the adjustment of the axes of the rollers 14 relative to the axis of the shaft 15, the carriage 1 will be moved in a forward or backward direction along the rails 8.

10 The adjusting device for the regulation of the speed of the carriage 1 and for the control of the movement of the carriage in a forward or backward direction comprises a plurality of levers 11, one end of which being firmly secured to the free ends of the spindles 18, the other end of which being rotatably engaged with recesses of racks 19 slidably mounted in the wall of the casing 13. A movement of said racks 19 causing a rotation of the spindles 18 and an adjustment of the angle between the axes of the rollers 14 and the shaft 15 through the levers 11 may be obtained by a rocking movement of a double toothed segment 20 engaging with said racks 19, arranged opposite to each other. The toothed segment 20 is secured to the inner end of a pin 21 journaled in the wall of the casing 13. The outer end of the pin 21 carries a ball-like member 22 slidably engaged with two parallel bars 23 extending over the entire length of the machine. These bars 10 are attached to the levers 24 rigidly mounted on the likewise continuous shaft 25. Mounted loosely rotatable on the shaft 25 is a lever 26 which, through the push rod 27, is shifted by a disc cam 28 from one limiting position into the other symmetrically corresponding one, at each reversal of the carriage 1.

15 A striking lever 29, which is rigidly mounted on the shaft 25, is resiliently coupled to the lever 26. The deflection of this lever 29 can be regulated by means of striking cams or stops 30 which can be shifted towards or away from each other on an adjusting spindle 31 which is provided with a left and right-handed thread and is moved by means of a hand-wheel 36. The weight of the actuating bars 23 and of the lever 24 is compensated by balance-weights 32.

20 The kind of elastic coupling between the levers 26 and 29 is normally kept in the mid-position of Fig. 3 by parts 33, whose striking pins 34 are connected together by a tension spring 35, so that the lever 29 oscillates with the lever 26 until it strikes against one of the stops 30. Then, against the tension of the spring 35, the lever 26 continues further in its movement, as shown in Fig. 3 whilst the lever 29—and with it the bars 23 as well as the friction rollers 14—remains in the position determined by the stop 30 for this particular stroke of the carriage.

25 By suitably shaping the flanks of the disc cam 28, it is possible to thus influence the reversing movements of the friction rollers 14 that the retarding and accelerating forces become uniform, regardless of the angular deflection to which the friction rollers have been set by adjusting the stops 30, and therefore independently of the speed of the carriage.

30 The flanks of the disc cam are to have such a shape that the retarding and accelerating forces reach nearly but not quite the sum of the friction forces exerted by the rollers 14 on the shaft 15 so that there is no danger of the rollers 14 sliding or slipping on the shaft 15 in the axial direction. Hereby the time used for reversing the carriage 75 will be the shortest possible one.

I claim:

1. A flat knitting machine comprising a needle bed, a carriage provided with knitting cams, rails forming a guideway, said rails being arranged above said needle bed, a U-shaped support for the suspension of said carriage above said needle bed, and a plurality of horizontally and vertically arranged rollers, said rollers being mounted on said U-shaped support and arranged to roll on surfaces of said rails for the movable arrangement of the U-shaped support on said guideway, the free ends of the legs of said U-shaped support being attached to intermediate points of said carriage, the legs of said U-shaped support being of a length providing a space between said guideway and said carriage and rendering the needle bed accessible. 10

2. A flat knitting machine comprising a carriage provided with knitting cams, a driving shaft adapted to be driven by a motor, an actuating casing, guiding members, said actuating casing being movably arranged on said guiding members, a coupling member, said coupling member connecting said carriage with said actuating casing, and actuating means, said actuating means being within said actuating casing and engaging with said driving shaft. 20

3. A flat knitting machine comprising a needle bed, a carriage provided with knitting cams, a guideway arranged above said needle bed, a support for the suspension of said carriage above said needle bed, said support being movably arranged on said guideway, means connecting said support with said carriage, a driving shaft adapted to be driven by a motor, an actuating casing, 30 guiding members arranged independently of said guideway, said actuating casing being movably arranged on said guiding members, a coupling member, said coupling member connecting said carriage with said actuating casing, and actuating means, said actuating means being within said actuating casing and engaging with said driving shaft. 35

4. A flat knitting machine comprising a needle bed, a carriage provided with knitting cams, a guideway arranged above said needle bed, a support for the suspension of said carriage above said needle bed, said support being movably arranged on said guideway, means connecting said support with said carriage, a driving shaft adapted to be driven by a motor, an actuating casing, guiding members arranged independently of said guideway, said actuating casing being movably arranged on said guiding members, a coupling member, said coupling member connecting said carriage with said actuating casing, actuating means adapted to operate said casing with different speeds and in opposite directions, said actuating means being within said actuating casing and engaging with said driving shaft, and adjusting means for the adjustment of the operation of said actuating means. 50

5. A flat knitting machine comprising a needle bed, a carriage provided with knitting cams, a guideway arranged above said needle bed, a support for the suspension of said carriage above said needle bed, said support being movably arranged on said guideway, means connecting said support with said carriage, a driving shaft adapted to be driven by a motor, an actuating casing, 70 guiding members arranged independently of said guideway, said actuating casing being movably arranged on said guiding members, a coupling member, said coupling member connecting said carriage with said actuating casing, friction roll- 75

ers, said friction rollers being adjustably arranged within said actuating casing and being pressed against said driving shaft, a mechanism adapted to adjust the angle between the axes of said friction rollers and said driving shaft for the operation of said casing with different speeds and in opposite directions, and a cam, said cam being connected with said mechanism for the control of the adjusting movements thereof.

6. A flat knitting machine comprising a needle bed, a carriage provided with knitting cams, a guideway arranged above said needle bed, a support for the suspension of said carriage above said needle bed, said support being movably arranged on said guideway, means connecting said support with said carriage, a driving shaft adapted to be driven by a motor, an actuating casing, guiding members arranged independently of said guideway, said actuating casing being movably arranged on said guiding members, a coupling member, said coupling member connecting said carriage with said actuating casing, friction rollers, said friction rollers being adjustably arranged within said actuating casing and being pressed against said driving shaft, a mechanism adapted to adjust the angle between the axes of said friction rollers and said driving shaft for the operation of said casing with different speeds and in opposite directions, a cam, said cam being connected with said mechanism for the control of the adjusting movements thereof, and adjustable stops adapted to limit the movements of said mechanism.

7. A flat knitting machine, comprising a needle bed, a carriage provided with knitting cams, a guideway arranged above said needle bed, a support for the suspension of said carriage above said needle bed, said support being movably arranged on said guideway, means connecting said support with said carriage, a driving shaft adapted to be driven by a motor, an actuating casing, guiding members arranged independently of said guideway, said actuating casing being movably arranged on said guiding members, a coupling member, said coupling member connecting said carriage with said actuating casing, friction rollers, said friction rollers being adjustably arranged within said actuating casing and being pressed against said driving shaft, a mechanism adapted to adjust the angle between the axes of said friction rollers and said driving shaft for the operation of said casing with different speeds and in opposite directions, a controlling member

rigidly connected to said mechanism and adapted to control the movements thereof, adjustable stops adapted to limit the movements of said controlling member, a cam adapted to actuate said controlling member, and elastic means arranged between said cam and said controlling member.

8. A flat knitting machine comprising a needle bed, a carriage provided with knitting cams, a support for the suspension of said carriage above said needle bed, said support having the form of an inverted U, rollers arranged on the upper portion of said support, a guideway arranged above said needle bed, said rollers contacting said guideway, said U-shaped support having its legs depending from its base to points below said guideway, and the free ends of the legs of said U-shaped support being attached to intermediate points of said carriage, thus providing a space between said guideway and said carriage and rendering the needle bed accessible.

9. A flat knitting machine comprising a needle bed, a carriage provided with knitting cams, uprights, said uprights being attached to said needle bed, a support for the suspension of said carriage above said needle bed, said support having the form of an inverted U, rollers arranged on the upper portion of said support, rails forming a guideway, said rails being arranged on said uprights above said needle bed, said rollers contacting said rails, said U-shaped support having its legs depending from its base to points below said guideway, and the free ends of the legs of said U-shaped support being attached to intermediate points of said carriage, thus providing a space between said guideway and said carriage and rendering the needle bed accessible.

10. A flat knitting machine comprising a needle bed, a carriage provided with knitting cams, a support for the suspension of said carriage above said needle bed, said support having the form of an inverted U, rollers arranged on the upper portion of said support, a guideway arranged above said needle bed, said rollers contacting said guideway, said U-shaped support having its legs depending from its base to points below said guideway, the free ends of the legs of said U-shaped support being attached to intermediate points of said carriage, thus providing a space between said guideway and said carriage and rendering the needle bed accessible, and driving means adapted to actuate said carriage.

VOLKHART WALTER MEHNERT.
